United States Patent Office

Des. 180,393

Patented June 4, 1957

180,393

BEAUTY SHOP CHAIR OR SIMILAR ARTICLE

Clarence Long Dlouhy, Chicago, Ill., assignor to Emil J. Paidar Company, Chicago, Ill., a corporation of Illinois

Application September 5, 1956, Serial No. 42,840

Term of patent 7 years

(Cl. D15—3)

Figure 1 is a front elevational view of the beauty shop chair or similar article, showing my new design;

I claim:

The ornamental design for a beauty shop chair or similar article, as shown.
